J. J. KUHNER

ELECTRIC WATER HEATER

Filed Oct. 2, 1920

Fig. 1.

UNITED STATES PATENT OFFICE.

JULIUS J. KUHNER, OF HIGHLAND, ILLINOIS.

ELECTRIC WATER HEATER.

Application filed October 2, 1920. Serial No. 414,290.

To all whom it may concern:

Be it known that I, JULIUS J. KUHNER, a citizen of the United States of America, and a resident of the city of Highland, in the county of Madison and State of Illinois, have invented certain new and useful Improvements in an Electric Water Heater, of which the following is a specification.

The primary object of this invention is to provide an improvement in heating containers which are adapted to be heated internally.

Another object of the invention is to provide an electric water heater with active controlling means.

A further object of this invention is to provide a water heater that is thermostatically controlled and in which the cold water receiving compartment is arranged so as to cause the thermostat to immediately become effective on the heating element as soon as the initial hot water pouring is in effect.

Other and further objects will appear in the specification and be specifically pointed out in the appended claims, reference being had to the accompanying drawings exemplifying the invention, and in which,

Figure 1 is a vertical section taken through this improved heating device.

Figure 2 is a horizontal section taken on the line II—II of Fig. 1.

Figure 3 is a front elevation of the electric switch and its operating mechanism taken in the direction of the arrow 3, Fig. 1.

Referring to the drawings, 1 designates a vertically extending container or compartment, and arranged above said container is a cold water receiving compartment 2, and leading from said compartment 2 and extending into the container 1 is an inlet tube 3. Extending through the bottom 4 of the container 1 is an inlet cold water pipe 5, which is connected with the supply pipe 6, said pipe 5 passing through the container 1 and communicating at 7 with the bottom 8 of the compartment 2.

Leading from the upper end of the container 1 and passing through the compartment 2 is an outlet pipe 9, which leads to the faucet 10 that is adapted to discharge into the bowl 11. Formed on the upper wall 12 of the compartment 2 is a boss 13, and secured to said boss above said wall 12 is a thermostat 14 bearing a bifurcated portion 15 on its upper surface, and hori-

zontally resting in said bifurcated portion is a lever 16 which is pivotally secured at one end to a support 17 which extends from the upper wall 12 of the compartment 2. Adjustably secured to the opposite end of said lever 16 is a depending operating rod 18, the lower end of said rod being secured to one end of an actuating lever 19 that is pivoted at 20 to an insulating block or plate 21 which is secured by studs 22 within the recess 23 formed in the lower portion of the front wall 24 of the container 1.

Depending from the opposite end of the lever 19 and pivotally secured thereto is a leg 25 bearing a roller 26 at its lower end, and connected to said leg and said lever is a spring 27, said spring causing the roller 26 to normally bear against either one of the cam surfaces 28 and 29 which are formed on one end of a contacting member 30 which is pivoted at 31 to the plate 21.

The member 30 has a contacting end 32 which is adapted to engage an adjustable terminal 33, and leading from said terminal is an electric circuit wire 34, and leading to the pivot 31 of said member 30 is a wire 35, said wire 35 leading from the electric plug 36 which is secured to the protruding stem 37 of an electric heating element 38 which is located within the container 1.

In the operation of this improved device, the container 1 and compartment 2 are filled with water from the source of supply 6, and assuming that the water in the container 1 and compartment 2 is at a low temperature, the rheostat 14 will be in its contracted form, in which the regulating rod 18 and lever 19 to which said rod is engaged at its lower end will be in the position shown in Fig. 3, and in which the circuit between the wires 34 and 35 will be closed on account of the contacting end 32 of the swinging member 30 bearing against the terminal 33, and in which electric current will be supplied to the heating element 38 from the electric supply wires 39. After the water in the container has become heated, the water in the compartment 2 will become heated through circulation of the water through the tube 3 which leads from said compartment as well as from the heat arising from the bottom 8 of said compartment, and the heat from the compartment 2 upon being radiated to the rheostat 14 will cause said rheostat to gradually expand, thereby elevating the rod engaging end of the lever

16 and elevating the rod 18, and the roller 26 which is carried by the leg 25 will be caused to move downwardly on the cam face 28 of the contacting member 30 until the 5 thermostat 14 has been expanded enough to cause the roller to travel on to the cam face 29, thereby underengaging the cam end of the member 30 and causing the contacting end 32 of said member 30 to swing downwardly from the terminal 33, thereby breaking the circuit, in which the heating energy will be cut off from the heating element 38.

In the event that the faucet 10 is operated for the discharge of hot water there- 15 through from the container 1, the water removed from said container will be replaced from water drained through the tube 3 from the compartment 2, said compartment being immediately supplied by cold water from 20 the cold water pipe 5 and as soon as the cold water enters said compartment the coolness radiated therefrom will immediately become effective on the rheostat 14, thereby contracting said rheostat and allowing the 25 lever 16 and rod 18 to be lowered on account of the activeness of the spring 27 on the lever 19, in which the roller 26 will be elevated and brought to bear on the upper cam surface 28, thereby causing the contacting 30 end 32 of the member 30 to swing upwardly and engage the terminal 33, thereby closing the circuit between the wires 34 and 35 so that heating energy can be again applied to the heating element 38.

35 In this connection it is to be noted that the hot water contents of the compartment 2 only have to be drained and in which said compartment is relatively small, before the heating energy is turned on, as against 40 if the whole body of hot water had to be drained from the large container 1. From the aforesaid it is to be seen that it is only necessary to withdraw a small amount of warm water for turning on the heating 45 energy, thereby providing a very accurate heating device.

What I claim is:—

1. A heating container comprised of a

pair of abutting compartments, one being 50 arranged above the other, a cold water connection leading to said upper compartment, a heating element associated with the lower compartment, a theormostatic regulator associated with said upper compartment and said heating element, and an outlet leading 55 from said upper compartment to said lower compartment.

2. A heating container comprised of a pair of compartments, one being arranged above the other, a cold water connection 60 leading to said upper compartment, an outlet leading from said upper compartment to said lower compartment, a draw-off connection leading from the upper end of said lower compartment, a heating element located in said lower compartment, a thermostat located on top of said upper compartment, a controlling mechanism co-operable with said thermestat, and an electric circuit 65 connecting said element and said mechanism. 70

3. In a water heating apparatus, the combination of a compartment, a cold water connection leading to and extending within said compartment, a heating element active upon the water of said compartment, a thermostat cooperable with said element, said thermostat being disposed whereby the temperature given from said cold water connection will become active thereon, and draw-off means for the discharge of water 75 heated by said element. 80

4. A water heating device comprised of a compartment, a cold water connection depending through said compartment to a point adjacent the bottom thereof, a discharge passageway leading from the upper end of said compartment, a heating element contained within said compartment, and a thermostatic controlling device located adjacent said cold water connection outside of 85 said compartment affected by the temperature of the water contained in said connection, said thermostat being associated with 90 said element.

JULIUS J. KUHNER.
